UNITED STATES PATENT OFFICE.

GARRET B. OSTERHOUT, OF NEW YORK, N. Y.

SINGLE-TRIGGER MECHANISM FOR GUNS.

No. 813,513.

Specification of Letters Patent.

Patented Feb. 27, 1906.

Application filed August 27, 1903. Serial No. 170,938.

To all whom it may concern:

Be it known that I, GARRET B. OSTERHOUT, a citizen of the United States, residing at No. 913 Greene avenue, in the borough of Brooklyn, in the city of New York, county of Kings, and State of New York, have invented a certain new and useful Improvement in Single-Trigger Mechanism for Guns, of which the following is a full, clear, and exact description, such as will enable others skilled in the art to which it appertains to make and use the same, reference being had to the accompanying drawings, which form a part of this specification.

Figure 1 is a vertical longitudinal section view. Fig. 2 is a plan view, the upper tang being broken away. Fig. 3 is a side elevation view with the plate which trips the right sear removed and shown in dotted outlines. Fig. 4 is a side elevation viewed from the right side. Fig. 5 is a side elevation viewed from the left side. Fig. 6 is a side elevation view showing an attachment whereby the mechanism may be shifted and the left sear tripped first. Fig. 7 is a bottom plan view of the shifting mechanism.

This invention relates to new and useful improvements in single-trigger mechanism for guns having a plurality of barrels, the object being to enable the operator to successively release or trip the firing mechanisms by the manipulation of a single mechanism in the form of a trigger and to prevent the discharge of the second barrel by the concussion caused by the discharge of the first barrel.

With this object in view my invention consists in the novel construction, arrangement, and combination of the several parts, all as will hereinafter be described, and afterward pointed out in the claims.

In the drawings, 1 indicates the barrels, 2 the frame, 3 the fore-end, 4 the pivot by which the barrels and fore-end are pivoted to the frame, 5 the top lever, by which the barrels are locked to the frame when the gun is closed, 6 the hammer, 7 the mainspring, 8 the left sear, 9 the right sear, and 10 the springs which operate the sears, 11 a post forming a part of or rigidly attached to the frame, all of which parts are practically the usual and well-known construction of the firearm commonly called "double-barreled hammerless shotgun."

The general construction and operation of a double-barreled hammerless shotgun are well understood and a detailed description is

hardly necessary, but for purposes of explanation may be briefly described as follows: The gun shown is of the breakdown type, and upon the release of the barrel-locking mechanism by the manipulation of the top lever 5 the barrels swing on the pivot 4, which in addition to actuating the ejecting mechanism also operates the cocking mechanism and brings the hammers to full-cock. 60 65

12 is a post rigidly attached to the frame, to which is pivoted an angle-plate 13 by means of the screw 14.

15 is a tripping member pivoted, by means of the screw 16, to the angle-plate 13. This 70 tripping member is provided with a slot 17, which registers with the left sear 8. It is also provided with a pin or shoulder 18, projecting from its inner face. Another tripping member 19 is pivoted to the frame of the 75 gun by the pin 24 and is fitted into the slot in the frame in which the trigger for the right barrel is usually fitted, and this tripping member 19 is provided with a slot 20, with which the sear 9 of the right lock of the gun 80 registers, also with a slot 21, which registers with a pin or projection 22 on the plate 13. 85

23 is the trigger, which is pivoted to the frame in the usual manner by the pin 24 and is provided with two shoulders 25 and 26. 85

When the hammers are at full-cock, the end of the right sear 9 is somewhat elevated, and the tripping member 19 is raised thereby, and the plate 13 and the tripping member 15, pivoted to the same, are forced forward in 90 such a position that the shoulder 25 of the trigger registers with the pin or shoulder 27 on the inner face of the plate 13, so that when the trigger is pulled the shoulder 25 is elevated and the plate 13 pushed upward, carrying with it the tripping member 19 and tripping the sear 9 of the right barrel. When the sear is tripped and the hammer falls, the tripping member 19 is forced downward and backward by the sear 9, and the plate 13 and the tripping member 15 pivoted thereto are forced backward, so that the pin or projection 18 on the tripping member 15 registers with the shoulder 26 on the trigger, and when the trigger is again pulled the shoulder 26 100 presses against the pin or shoulder 18, and the tripping member 15 is elevated and the sear 8 of the left lock tripped and the left barrel discharged. 105

On the post 11 is a shoulder or pin 28, beneath which the tripping member 15 is forced when both locks of the gun are cocked. This 110

prevents the tripping member 15 from being elevated and locks the sear of the left lock, so that the left barrel cannot be discharged until the right barrel has been fired and the pressure on the trigger has been released and the mechanism forced backward by the falling of the sear 9, when the left barrel has been discharged.

29 is a spring for taking up the lost motion of the trigger.

In operation the recoil resulting from the discharge of the right barrel releases the pressure of the finger upon the trigger, so that the angle-plate 13 and the tripping member 15 are free to move backward under pressure of the sear 9, and the parts are then in position for discharging the left barrel.

It is sometimes desirable to fire the left barrel first. I have shown in Figs. 6 and 7 a projecting part 30, forming a part of the plate 13, which extends beyond the frame of the gun and has a spring portion 31 and angular grip-piece 32 and a catch 33, adapted to engage the recess 34 in the frame. When it is desired to fire the left barrel first, the finger is placed against the angular grip-piece 32 and the parts are drawn backward until the catch 33 engages with the recess 34, which retains the tripping member 15 in position to engage with the trigger and trip the left sear.

Having thus described my invention, what I claim, and desire to secure by Letters Patent, is—

1. In a gun a safety device which consists of a shoulder or projection on the frame of the gun and a longitudinally-movable tripping member engaging with the sear, which is adapted to be interposed between said shoulder or projection and the end of the sear so that the sear cannot be released and means for moving said tripping member out of engagement with said shoulder or projection so that the mechanism can be fired, substantially as and for the purposes described.

2. In a gun a safety device which consists of a shoulder or projection on the frame of the gun, a sear and a longitudinally-movable tripping member and means for interposing said tripping member between such shoulder or projection and the end of the sear and means for moving said tripping member out of engagement with said shoulder or projection so that the mechanism can be fired, substantially as and for the purposes described.

3. In a safety device for double-barreled guns, the combination with a shoulder on the frame of the gun of a sear a movable tripping member engaging with the sear and automatic means for moving said tripping member into engagement with said shoulder when the firing mechanism is cocked and automatic means for moving such tripping member out of engagement with said shoulder when the other sear has been tripped, substantially as and for the purposes described.

4. In a safety device for double-barreled guns, the combination with separate firing mechanisms for each barrel, including in each mechanism a hammer, a sear and a tripping member in engagement with the sear of a shoulder on the frame of the gun, one of said tripping members being adapted to be moved into engagement with said shoulder and lock said sear so that it cannot be tripped, automatic means for moving said tripping member into engagement with said shoulder when the firing mechanism is cocked and automatic means for moving said tripping member out of engagement with said shoulder when the second sear is tripped, substantially as 80 and for the purposes set forth.

5. In a single trigger, the combination with a plurality of firing mechanisms in which are included hammers and sears, of a single trigger, two tripping members engaging respectively with said sears and a swinging member pivoted to the frame of the gun, one of said tripping members being pivoted at its forward end to the frame of the gun and the second tripping member being pivoted at its rear end to said swinging member and means whereby the movement of the first tripping member is communicated to the swinging member and the second tripping member, and the second tripping member is shifted 95 into engagement with the single trigger, substantially as and for the purposes described.

6. In a single trigger, the combination with a plurality of firing mechanisms in which are included hammers and sears, of a single trigger, a tripping member adapted to engage with one of said sears and pivoted at its forward end to the frame of the gun, a second tripping member engaging with the second sear and engaging at its rear end with a 100 swinging member pivoted to the frame of the gun and means whereby the first tripping member is depressed when the sear with which it is in engagement is tripped and the second tripping member is shifted backward 110 into engagement with the trigger mechanism, substantially as and for the purposes described.

7. In a single trigger, the combination with a plurality of firing mechanisms in which are 115 included hammers and sears, of a single trigger, two tripping members engaging respectively with said sears and intermediate mechanism engaging with both of said tripping members and means whereby one of the tripping members is forced downward when the sear with which it is engaged is tripped and the second tripping member is forced backward and into engagement with the trigger mechanism, substantially as and for the purposes described.

8. In a single-trigger mechanism, the combination with a plurality of firing mechanisms in which are included hammers and sears, of a single trigger, two tripping mem-

- bers engaging respectively with said sears and intermediate mechanism engaging with both of said tripping members and means whereby one of the tripping members is forced downward when the sear with which it is engaged is tripped and the second tripping member is forced backward and into engagement with the trigger mechanism, substantially as and for the purposes described.
9. In a single-trigger mechanism, the combination with a plurality of firing mechanisms, in which are included hammers and sears, of a single trigger, tripping members engaging respectively with said sears, one of which is pivoted at its forward end to the frame of the gun and the other at its rear end to a swinging member supported on the frame of the gun, means whereby one of the tripping members is forced downward when the sear with which it is in engagement is tripped and means whereby the second tripping member is forced backward and into engagement with the trigger mechanism when the first tripping member is forced downward, substantially as and for the purposes described.
10. In a single-trigger mechanism, the combination of a plurality of firing mechanisms, in which are included hammers and sears, of a single trigger, a tripping member adapted to engage with one of said sears and pivoted at its forward end to the frame of the gun, a second tripping member engaging with the second sear and pivoted at its rear end to a swinging angular plate pivotally mounted on the frame of the gun, means for depressing the first sear and tripping member when the first sear is tripped, and intermediate mechanism whereby the second tripping member is shifted backward and into engagement with the trigger mechanism by the downward movement of the first sear and its tripping mechanism when the first sear is tripped, substantially as and for the purposes described.
11. In a single-trigger mechanism, the combination with a sear of a tripping member engaging therewith, a second sear and a second tripping member engaging with said second sear and a member pivoted to the frame of the gun and engaging with both of said tripping members and adapted to transmit motion from the first tripping member to the second tripping member, substantially as and for the purposes described.
12. In a single-trigger mechanism, the combination with a plurality of firing mechanisms, in which are included hammers and sears, of two tripping members engaging respectively with said sears, a swinging member pivoted to the frame of the gun, one of such tripping members being pivoted at its forward end to the frame of the gun and a second tripping member being pivoted at its rear end to said swinging member and the first tripping member being also mechanically connected to said swinging member, substantially as and for the purposes set forth.
13. In a single-trigger mechanism, the combination with a plurality of firing mechanisms, in which are included hammers and sears, of two tripping members respectively engaging with said sears, a swinging member pivoted to the frame of the gun, one of said tripping members being pivoted at its forward end to the frame of the gun and the hammer of the firing mechanism with which said tripping member co-operates being so cut away that the rear of the sear is forced downward when the mechanism is fired and the second tripping member being pivoted at its rear end to said swinging member and the first tripping member being also in mechanical connection with said swinging member so that any movement of the first tripping member will impart movement to the swinging member and through it to the second tripping member, substantially as and for the purposes described.
14. In a single-trigger mechanism, the combination with a plurality of firing mechanisms in which are included hammers and sears, one of said hammers being cam-shaped so that when the hammer has fallen the rear end of the sear will be depressed, of a tripping member engaging with such sear and pivoted at its forward end to the frame of the gun, a second tripping member engaging with the second sear and pivoted at its rear end to a swinging member pivotally supported on the frame of the gun and a single trigger constituting means whereby the second tripping member is forced out of engagement with the single trigger when the firing mechanisms of both barrels are cocked and moved into engagement with the single trigger by the tripping of the first sear, substantially as and for the purposes described.
